F. A. CRAMBLITT, OF PETROLEUM CENTRE, PENNSYLVANIA, ASSIGNOR
TO HIMSELF AND JOSEPH R. DICKEY.

Letters Patent No. 67,417, dated August 6, 1867.

IMPROVEMENT IN PUMP-PISTONS.

The Schedule referred to in these Letters Patent and making part of the same.

TO ALL WHOM IT MAY CONCERN:

Be it known that I, F. A. CRAMBLITT, of Petroleum Centre, in the county of Venango, and State of Pennsylvania, have invented a new and useful Improvement in Pistons for operating pumps in oil, salt, artesian, or other deep wells; and I do hereby declare the following to be a full, clear, and exact description thereof, reference being had to the accompanying drawings, making a part of this specification, in which—

Figure 1 is an outside view of my improved piston, and

Figure 2 represents a vertical section passing longitudinally through its axis.

Like letters of reference indicate like parts.

The nature of my invention consists in the construction of a self-packing piston for operating oil, salt, artesian, or other wells of considerable depth. Such wells are commonly of small bore, and when at all productive are filled with a column of oil or water, or both. The obstacles which chiefly prevent the successful operation in such wells of the pistons ordinarily employed, consist in the great difficulty of packing a piston, so that when operated near the bottom of such well, and under a column of water or oil of from one hundred to one thousand or more feet in height, it will work successfully, and the packing not require frequent renewal in consequence of the wear and tear to which it is subject. Such a piston must be so constructed and provided with such packing in order to be successful that it can easily be sunk to the place in the tubing where it is to be operated, whatever may be the depth, and must possess sufficient strength, and work with sufficient tightness to sustain and carry up with its upward stroke whatever oil or water may be above, and draw up a fresh supply, if need be, for the next upward stroke, and all this with the least possible liability to get out of order.

To enable others skilled in the art to make and use my invention, I will proceed more particularly to describe its construction and mode of operation.

In manufacturing I employ any known materials in general use adapted to the purposes hereinafter to be designated.

a is a portion of the piston-rod, and by the thimble *b* is connected with other rods leading to the top or mouth of the well, though other modes of jointing may be used, if preferred. Commonly I cut a screw-thread, *a'* on the lower end of the rod *a*, for convenience in raising or lowering the stand-box, drawing tubing, etc. The upper end of the rod *a* plays through a hole or aperture in the arch *c*, and its lower end through the inverted arch *c'*. Attached to the lower and upper ends of the arches *c* and *c'* respectively are the barrels *d* and *d'*. Their outer diameters being equal to or slightly less than the inner diameter of the well-tubing or pump-barrel in which they work. The lower and upper ends of the barrels *d* and *d'* respectively are reamed out sufficiently to make room for the ends of the packing-pipe or sleeve *e*, which I make usually of leather or other flexible material. The ends of the packing-sleeve *e* are screwed into or otherwise secured beneath or inside the lower and upper ends of the barrels *d* and *d'* respectively, and held firmly between them and the inner pipes *f* and *f'*, which latter are screwed into the heads of the barrels *d* and *d'*, screw-threads, as shown in the drawings, being properly cut for such purposes. The other ends of the pipes *f* and *f'* are made to fit one into the other loosely, so as to allow the oil or water in the well to flow out between such ends and fill the empty space *s* between them and the packing-sleeve *e*, or if there be no such empty space, to press against the inner surface of the packing sleeve at that point, and force it into close contact with the tubing of the well.

The several parts are screwed together, as described, and in such a way that the ends of the packing-sleeve *e* shall be securely held between the barrels *d* and *d'* and the pipes *f* and *f'* respectively; also, so that the end *m* of one pipe *f* shall be distant about one-half or five-eighths of an inch, more or less, from the shoulder *m'* of the other pipe *f'*, thus allowing room for slight play to the upper-barrel *d* and pipe *f*, both working loosely on the rod *a*. The ends *m* and *n* of the pipes *f* and *f'* must also be so fitted or adjusted to each other as to permit the oil or water in the well to flow out between them against the packing-sleeve *e*, as above mentioned. Attached to the rod *a*, between the inverted arch *c'* and the head of the barrel *d'*, is a bucket, *o*, of such diameter and so fitted that when with the upward stroke it comes against the head of the barrel *d'*, it will make a joint therewith nearly or quite water-tight.

The mode of operating the devices thus described is simple: The piston thus constructed is sunk to the

point desired, and by piston-rods attached to an engine or other machine for communicating power at the mouth of the well. The upward stroke carries the bucket *o* upward, so as to close the aperture of the pipe *f*', and thereby prevent the contents of the well from passing downward through the piston as the piston rises. The upward movement of the piston-rod *a* then carries the whole piston up, and the oil or water escaping outward between the ends *m* and *n* of the pipes *f* and *f*', presses the packing-sleeve *e* against the tubing of the well, and renders it a tight packing. The upper half of the piston has sufficient play to fall slightly as the packing-sleeve *e* expands. The ends of the packing-sleeve *e* being securely fastened, as above described, no oil or water can escape downward through the piston, and the entire contents of the well necessarily are carried upward, causing the required discharge from the mouth of the well. The thimble *b* is so adjusted on the piston-rod *a* that the thimble *b* will strike the top of the arch *c* with the downward stroke of the piston, nearly or exactly at the same time that the bucket *o* strikes the top of the inverted arch *c*', so as to carry the whole piston down at once and prevent all possibility of the separation of the two halves of the piston, and consequently remove all danger of either end of the packing-sleeve *e* being drawn out of its socket. A collar encompassing the rod *a* at that point may take the place of the thimble *b*. As a further security against the packing-sleeve *e* working loose while the piston is being lowered or operated, I fasten it to the barrels *d* *d*' and pipes *f* *f*', by pegs or pins *u* *u* running through holes *u* *u* drilled for the purpose, and also through the packing-sleeve *e*, near its ends. Common shoe pegs are usually sufficient for this purpose. The sleeve *e* cannot then be unscrewed, and the two ends of the piston are prevented from separating sufficiently to enable it to be drawn out. The upper half of the piston has play enough to allow the packing-sleeve *e* to be pressed out as described, but not enough to allow it to be crumpled down or wrinkled. I thus secure a piston packing, convenient, tight, self-acting, and not liable to get out of order, and as the friction of the outer face of the flexible packing-sleeve *e* against the tubing of the well is inconsiderable, the packing thus described is exceedingly durable, and when worn out can be easily renewed. As the two halves of the piston thus constructed are counterparts to each other, the piston may be reversed on the piston-rod *a* in case the lower end of the piston should become worn or injured so as not to make a sufficiently tight joint with the bucket *o*.

Numerous variations of form may be introduced in the devices above described, without seriously injuring their practical working. What I claim as new, and as the essential features of my invention, in addition to certain combinations of devices, some of which devices are already in use, is substantially as follows: The making of the two ends of the piston separate, so that one or both may have sufficient vertical play to admit of the outward expansion of the packing-sleeve *e*; also, so fitting the ends of such half pistons to each other as to leave room between them, or make holes or slots through them, so that the oil or water in the piston may pass out, and by its pressure slightly expand the flexible packing-sleeve *e*, and make it press snugly against the tubing of the well or the pump-barrel in which it is worked; also, providing such a piston with a packing-sleeve of leather or other flexible material, the ends of which shall be so secured to the upper and lower halves of the piston described as to make therewith tight working joints, and making the two ends of the piston counterparts to each other, so as to secure a reversible piston.

I claim, furthermore, the mode of packing above described by a packing-sleeve, *e*, of leather or other flexible material adapted to such uses, as applied to all pistons for operating deep wells, not only when such pistons are made in halves, as hereinbefore set forth, but also when they are made, as I sometimes make them, with the barrels *d* *d*' connected by a single pipe or tube. In such case I make slots or holes through such pipe or tube about midway between its two ends, through which the water or oil in the pump may pass out against the inner surface of the sleeve *e*, substantially as above described, and for the same purposes. The mode of using the packing-sleeve *e*, in connection with such single tube, and the mode of securing its ends to the barrels *d* *d*' does not vary materially from those above described.

What I claim as my invention, and desire to secure by Letters Patent, is—

1. Making in separate parts the two ends of a piston for operating pumps in oil, salt, artesian, or other deep wells, and attaching such parts to the piston-rod in such a way that one or both may have sufficient vertical play on the rod to admit of the outward expansion or bulging of the piston packing, substantially as and for the purposes described.

2. Fitting the contiguous ends of such half piston to each other, so as to leave room between them for the oil or water in the piston to pass out against and expand or bulge the piston packing, substantially as and for purposes above set forth.

3. Packing a piston for deep-well pumps by a packing-sleeve of leather, or other flexible material, in such a way that the ends of such sleeve shall be securely fastened beneath the outer surface of the upper and lower ends of such piston, so as to make therewith tight working joints, substantially in the manner and for the purposes above specified.

4. Making the half piston described counterparts of each other, so as to secure a reversible piston, substantially as and for the purposes described.

In testimony whereof I, the said F. A. CRAMBLITT, have hereunto set my hand in presence of—

F. A. CRAMBLITT.
